CLAIM

The ornamental design for a rotating display, as shown and described.

DESCRIPTION

FIG. 1 is a front elevation view of a first embodiment of the rotating display, side and rear views being mirror images thereof;

FIG. 2 is a perspective view thereof;

FIG. 3 is a perspective view thereof with a rotated module; and

FIG. 4 is a top plan view thereof;

FIG. 5 is a front elevation view of a second embodiment of the rotating display, side and rear views being mirror images thereof;

FIG. 6 is a perspective view thereof;

FIG. 7 is a perspective view thereof with a side panel partially pulled out;

FIG. 8 is a perspective view thereof with rotated module; and

FIG. 9 is a top plan view thereof;

FIG. 10 is a front elevation view of a third embodiment of the rotating display, side and rear views being mirror images thereof;

FIG. 11 is a perspective view thereof;

FIG. 12 is a perspective view thereof with rotated module; and,

FIG. 13 is a top plan view thereof.

The portions of the rotating display shown in broken lines form no part of the claimed design.
